UNITED STATES PATENT OFFICE.

JAMES P. TIERNEY, OF BROCKTON, MASSACHUSETTS.

SHOE MACHINERY.

Application filed December 6, 1922. Serial No. 605,185.

To all whom it may concern:

Be it known that I, JAMES P. TIERNEY, a citizen of the United States, residing at Brockton, in the county of Plymouth and State of Massachusetts, have invented certain new and useful Improvements in Shoe Machinery, of which the following is a specification, reference being had to the accompanying drawings.

10 This invention relates to certain improvements in shoe machinery and has relation more particularly to a machine having novel and improved means whereby a crease may be produced as desired in the upper 15 of a shoe to increase the aesthetic value of the shoe.

Another object of the invention is to provide a novel and improved machine comprising a creasing roller rotating about a 20 fixed axis together with a member movable toward or from the creasing roller and embodying a pair of under creasing rolls in cooperation with the first named creasing roll to produce the desired crease within the 25 work.

Another object of the invention is to provide a machine of this general character comprising an upper creasing roll which contacts with a pair of spaced under creasing 30 rolls and wherein means are interposed between the under creasing rolls to serve as a depth gauge for the crease produced within the work.

An additional object of the invention is 35 to provide a novel and improved machine of this general character comprising an upper creasing roll with a pair of under creasing rolls, said under creasing rolls having relative axial movement together with means for 40 constantly urging the under creasing rolls one toward the other together with an element interposed between the under creasing rolls to maintain a set width therebetween.

The invention consists in the details of 45 construction and in the combination and arrangement of the several parts of my improved shoe machinery whereby certain important advantages are attained and the device rendered simpler, less expensive and 50 otherwise more convenient and advantageous for use, as will be hereinafter more fully set forth.

The novel features of my invention will 55 herein after be definitely claimed.

In order that my invention may be the better understood, I will now proceed to describe

the same with reference to the accompanying drawings, wherein:

Figure 1 is a view in elevation with portions broken away, of a machine constructed in accordance with an embodiment of my invention;

Figure 2 is an enlarged vertical sectional view taken through the device as illustrated in Figure 1, said line of section being between the under creasing rolls and distorted to show the upper creasing roll in elevation;

Figure 3 is a fragmentary view in plan illustrating the depth gauge;

Figure 4 is an enlarged fragmentary view partly in longitudinal section and partly in elevation illustrating the detail mounting of the under creasing rolls and the location of the depth gauge;

Figure 5 is an enlarged fragmentary view partly in elevation and partly in section illustrating a modified construction to complete the crease structure of the upper of a shoe or the like;

Figure 6 is a view in perspective of an article produced by my improved machinery.

As disclosed in the accompanying drawings, 1 denotes a base of suitable design and preferably formed of cast iron and which is 85 provided at its top with a table 2 and a head 3 overlying said table. The head 3 rotatably supports a horizontally disposed shaft 4 adapted to be driven in any desired manner as by a pulley 5 or the like.

Fixed to the shaft 4 is the upper creasing roll 6 provided at substantially its transverse center with an outstanding and circumferentially disposed rib or bead 7. The upper creasing roll 6 is positioned above an opening 8 provided in the table 2 with the rib or bead 7 positioned substantially directly above an arm 10. The arm 10 is substantially perpendicularly related to the shaft 4 and bridges the opening 8 in the table 2, the opposite end portions of said arm 10 being secured as at 11 to the table 2, such connections preferably comprising removable screws so that the arm 10 can be applied or removed as may be desired. This arm 10 serves as a depth gauge and in a manner to be hereinafter more particularly referred to.

The forward face of the base 1 and at the lower portion thereof is provided with the spaced vertically disposed guides 12 between which is snugly engaged the slide

14. The slide 14 is maintained between the guides 12 by the plate 15 which has its opposite marginal portion secured by the screws 16 or the like to the outer faces of 5 the guides 12, whereby the plate 15 bridges the space between the guides 12.

The lower portion of the plate 15 at substantially its transverse center is provided with a vertically disposed slot 17 the upper 10 edge of which being defined by an outstanding lug 18. Threaded through the lug from above is a bolt 19, the lower end of which is adapted to contact an outstanding lug 20 carried by the lower portion of the slide 15 14, said lug 20 being directed through the opening 17. By this means the extent of upward movement of the slide 14 may be regulated or controlled in accordance with the necessities of practice.

20 The lower or bottom ends of the guides 12 are connected by the strip or elongated member 21 through the central portion of which is freely disposed the operating rod 22 for the slide 14, the upper portion of 25 said rod 22 being threaded as at 23 or otherwise connected with the slide 14. The rod 22 is adapted to have engaged therewith any means which can be employed with convenience and facility to impart downward 30 movement to the slide 14.

The lower face of the slide 14 at opposite sides of the lug 20 is provided with sockets 14' in which are positioned the expansion coil springs 24. The lower ends of the 35 springs are engaged with discs 25 snugly fitting therein and having direct contact with the upper ends of the screws 26. The screws 26 are threaded from below through the elongated member or strip 21. 40 As the slide 14 is moved downwardly the springs 24 are placed under compression whereby it is assured that upon release of the pull upon the slide 14 the same will be moved upwardly as desired. The lower 45 ends of the screws 26 are preferably provided with knurled heads 27 to facilitate the desired rotation thereof to regulate the tension of the springs 24 as may be required.

50 The upper portion of the slide 14 is provided with a pair of upstanding aligned bearings 28 which slidably support the shaft 29, said shaft 29 being in parallelism with the shaft 4 heretofore referred to and positioned directly therebelow. The upper portion of the slide 14 is provided with an arm 30 terminating in an upstanding bearing 31 to provide an additional support for the shaft 29.

60 Keyed with the shaft 29 for rotation therewith but having movement lengthwise of said shaft are the under creasing rolls 32 which are constantly urged one toward the other through the instrumentality of the 65 expandible members 33 herein disclosed as

coil springs and encircling the shaft 29, each of said members or springs being interposed between a roll 32 and tension collars 34 fixed to the shaft. The rolls 32 underlie the opposite marginal portions of the upper roll 70 6 and are arranged at opposite sides of the arm or depth gauge 10 hereinbefore referred to. Interposed between the rolls 32 is a spacing collar 35 which serves to maintain a set width between the under rolls 32 to 75 protect the rib or bead 7 of the upper roll 6.

The end portions of the shafts 4 and 29 adjacent the pulley 5 are provided with the coacting gears 36 whereby the desired rotation may be imparted to the rolls 6 and 32.

My improved machine as hereinbefore described is particularly adapted for use in producing in a desired portion of the upper 80 of a shoe an outstanding crease to enhance the aesthetic value of the shoe, said crease *a* being produced in the work W by the rolls 6 and 32. After the crease has been produced a reinforcing cord *b* is placed therein and the cord is maintained in applied 85 position by a rubberized fabric strip *c* or the like.

The work W, in producing the crease *a* is passed between the rolls 6 and 32 and in 90 order to facilitate the application or removal of the work, when desired the slide 14 may be depressed but, as hereinbefore set forth, the under rolls 32 will be constantly urged toward the rolls 6 by the action of the expandible members or springs 95 24. The crease produced is assured of a fixed depth throughout its length by the arm or gauge 10 which is positioned directly below the rib or bead 7 of the roll 6.

To assure the creation of a permanent crease *a* the rolls 6 and 32 may be heated electrically or otherwise as may be preferred but as illustrated in Figure 1 I show means for heating only the upper roll 6, said means comprising gaseous fuel burners 37 arranged at opposite sides of the roll 6.

Figure 5 of the accompanying drawings illustrates a further embodiment of my machine and which is adapted to roll down the cord *b* and the strip *c* and wherein the flat under rolls 32' are mounted upon the shaft 29 in lieu of the rolls 32 and mounted upon the shaft 4 in lieu of the upper rolls 6 is a relatively broad pressure roll 6' but aside from these changes the machine is constructed and operated in the same manner as hereinbefore described.

From the foregoing description it is thought to be obvious that a shoe machine 125 constructed in accordance with my invention is particularly well adapted for use by reason of the convenience and facility with which it may be assembled and operated, and it will also be obvious that my invention 130

is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:—

10 1. A machine of the class described comprising a table, a vertically movable slide positioned below the table, a shaft carried by the slide, rolls keyed to the shaft for rotation therewith but having movement lengthwise of the shaft, means for urging the rolls one toward the other, a roll supported above the table, said table having an opening through which the under rolls are adapted to extend, and means for constantly 15 urging the slide upwardly.

20 2. A machine of the class described comprising a table, a vertically movable slide positioned below the table, a shaft carried by the slide, rolls keyed to the shaft for rotation therewith but having movement lengthwise of the shaft, means for urging the rolls one toward the other, a roll supported above the table, said table having an opening through which the under rolls are 25 adapted to extend, means for constantly urging the slide upwardly, and a member interposed between the under rolls for limiting the movement thereof one toward the other.

30 3. A machine of the class described comprising a table, a vertically movable slide positioned below the table, a shaft carried by the slide, rolls keyed to the shaft for rotation therewith but having movement lengthwise of the shaft, means for urging the rolls one toward the other, a roll supported above the table, said table having an opening through which the under rolls are 35 adapted to extend, means for constantly urging the slide upwardly, and a gauge arm extending across the opening of the table and positioned between the under rolls.

40 4. A machine of the class described comprising a table, a vertically movable slide positioned below the table, a shaft carried by the slide, rolls keyed to the shaft for rotation therewith but having movement lengthwise of the shaft, means for urging

the rolls one toward the other, a roll supported above the table, said table having an opening through which the under rolls are adapted to extend, means for constantly urging the slide upwardly, and means for regulating the upward movement of the slide. 55

5. A machine of the class described comprising a table, a vertically movable slide positioned below the table, a shaft carried by the slide, rolls keyed to the shaft for rotation therewith but having movement lengthwise of the shaft, means for urging the rolls one toward the other, a roll supported above the table, said table having an opening through which the under rolls are 60 adapted to extend, means for constantly urging the slide upwardly, and a gauge arm extending across the opening of the table and positioned between the under rolls, said last named roll being provided with a circumferentially disposed bead positioned between the under rolls and substantially directly above the gauge arm. 65

6. A machine of the class described comprising a table, a vertically movable slide positioned below the table, a shaft carried by the slide, rolls keyed to the shaft for rotation therewith but having movement lengthwise of the shaft, means for urging the rolls one toward the other, a roll supported above the table, said table 70 having an opening through which the under rolls are adapted to extend, means for constantly urging the slide upwardly, and means for rotating the shaft and the last named roll. 75

7. A machine of the class described comprising an upper roll, a slide, a pair of spaced under rolls carried by the slide for coaction with the upper roll, a gauge member extending between the under rolls and underlying the upper roll, means for rotating the rolls, and means for constantly urging the under rolls toward the upper roll. 80

8. A machine of the class described comprising a table, coacting rolls supported for rotation above and below the table, said table having an opening through which certain of the rolls are adapted to extend, and a gauge arm extending across the opening of the table. 85

In testimony whereof I hereunto affix my signature.

JAMES P. TIERNEY.
